FLUID MIXING DEVICE

Elie P. Aghnides, 46 W. 54th St., New York, N.Y.
Filed Aug. 2, 1956, Ser. No. 601,712
6 Claims. (Cl. 239—431)

The present invention relates to improved fluid mixing devices, for instance of the type which may be employed in aerating liquids, and is particularly concerned with improved such structures which include a single easily removable and cleanable unit within a casing. The present application comprises a continuation-in-part of my prior copending applications Serial No. 135,645, filed December 29, 1949, for "Fluid Mixing Device," now U.S. Patent No. 2,811,340 issued October 29, 1957; and Serial No. 424,981, filed April 22, 1954, for "Fluid Mixing Device."

Various structures have been suggested in the past for intimately mixing two or more fluids of which at least one of the fluids is under pressure, and a typical such structure is shown in my U.S. Patent No. 2,210,846, granted August 6, 1940, for "Fluid Mixing Device." Such fluid mixing devices ordinarily comprise a casing adapted to be connected to a source of fluid (for example water) under pressure, and the said casing ordinarily includes a chamber through which the fluid may flow. The casing is also ordinarily provided with openings which lead into the aforementioned chamber for the introduction of one or more other fluids, for example air or gases, which are either entrained into the said chamber due to flow of liquid or fluid therethrough, or which reach the chamber under their own power. Means are also provided in the path of the first-named fluid for finely breaking up the said first-named fluid and for offering sufficient resistance for mixing it with the other fluid or fluids.

Typical fluid mixing or aerating structures of the type described ordinarily include a plurality of screens and/or diaphragms spaced from one another and located within the aforementioned casing at desired locations with respect to the several fluid inlets and outlets of the said casing for performing the functions detailed above, and these several screens and/or diaphragms often take the form of individual parts which are supported within the casing. Upon occasion, it is desirable to clean these several parts, and as a result, the said parts are sometimes removed from the casing whereby one or more of the said parts may in fact become lost. The several parts which have been employed in the past further complicate the problems of removing and replacing these parts and require that special care and attention be given so as to assure that the several parts are correctly reassembled within the casing to permit the overall structure to perform its aerating or fluid mixing function properly. It will be appreciated from the foregoing discussion, therefore, that various aerating structures suggested heretofore are relatively complex in construction and often comprise a relatively large number of parts which must be assembled in a precise manner, and these parts may, upon occasion, become separated and lost. As a result, such prior aerating structures have not lent themselves readily to disassembly for cleaning purposes.

The present invention serves to obviate the foregoing difficulties and is particularly concerned with an improved fluid mixing device or aerator which includes an improved diaphragm structure which may be so fabricated and arranged with respect to the remainder of the aerator device that, through cooperation of two diaphragms with one another, or through cooperation of one or more of the said diaphragms with the aerator body itself, a plurality of openings may be formed within an aerator casing. These openings may take the form of one or more orifices

2

at one level spaced from one or more orifices at another level, or they may take the form of one or more annular orifices disposed within the casing at different levels and serve to finely divide or spread a stream of liquid or fluid under pressure, thereby to permit that stream of liquid or fluid to be more thoroughly mixed with other fluids, such as gases. In accordance with a particular feature of the invention, the improved diaphragm arrangements take the form of a single easily removable and cleanable unit which, by cooperation with a member or with the casing itself, forms a plurality of orifices at different parallel levels; the orifice or orifices at the upstream level being, preferably, out of alignment with the orifice or orifices at the downstream level, whereby an improved fluid mixing device or aerator in accordance with the present invention can be readily disassembled for cleaning purposes and can thereafter be assembled without the possibility of parts being lost and without the possibility of incomplete cleaning or improper assembly.

It is accordingly an object of the present invention to provide an improved fluid mixing device.

Still another object of the present invention resides in the provision of improved diaphragm arrangements for use in fluid mixing devices whereby the said diaphragm arrangements may take the form of an easily removable and cleanable unit.

A still further object of the present invention resides in the provision of a fluid mixing device or aerator having fewer parts than those suggested heretofore.

Another object of the present invention resides in the provision of a fluid mixing device which may be more readily cleaned than other devices suggested heretofore and which reduces the possibility of incorrect assembly or loss of parts during and subsequent to such a cleaning operation.

A still further object of the present invention resides in the provision of improved diaphragm structures for use in fluid mixing devices or aerators whereby the overall structure is less expensive to manufacture than others suggested heretofore.

Other objects and advantages of the present invention will be readily apparent to those skilled in the art as this description proceeds.

In providing for the foregoing objects and advantages, the present invention contemplates the provision of an improved fluid mixing device or aerator comprising a casing having means at one end thereof for attaching the said casing to a source of fluid, such as water, under pressure. The casing further defines, downstream of the said fluid inlet end, a fluid outlet and one or more screen elements may be disposed adjacent the said fluid outlet. One or more air inlets are also provided in the casing and these air inlets serve to introduce air, or other fluids to be mixed with the aforementioned fluid under pressure, to a mixing region intermediate the inlet and outlet ends of the casing. This mixing region further includes, in accordance with the present invention, an improved diaphragm arrangement comprising a single easily removable and cleanable unit and in accordance with particular forms of the present invention, this diaphragm arrangement may take the form of a substantially conical body which may have webs thereon, the said webbed conical body being so disposed in the mixing chamber of the aerator that it serves to break up the aforementioned fluid under pressure as it passes through the casing, thereby to permit an intimate intermixing of the said fluid with other fluids, such as air, which may be introduced in the casing, whereby the overall structure effects an aerated fluid outlet. As will become apparent from the following description, the aforementioned conical or webbed conical body comprising the improved diaphragms of the present arrangement, may

cooperate with the aerator casing itself, or various parts of the said diaphragm structure may cooperate with one another, whereby desired apertures are produced for breaking up a stream of fluid passing through the casing thereby to permit the desired intermixing of that fluid with air.

The foregoing objects, advantages, construction and operation of the present invention will become more readily apparent from the following description and accompanying drawings, in which:

FIGURE 1 is a cross-sectional view of an improved fluid mixing device constructed in accordance with one form of the present invention.

FIGURE 2 is a cross-sectional view taken along line 2—2 of FIGURE 1.

FIGURE 3 is a sectional view of another form of fluid mixing device or aerator device constructed in accordance with the present invention.

FIGURE 4 is a cross-sectional view of still another embodiment of the present invention.

FIGURE 4A is a view taken on line A—A of FIGURE 4; and

FIGURE 5 is a cross-sectional view of still another form of fluid mixing device constructed in accordance with the present invention.

In connection with the description of all of the forms of the invention, it is understood that the casing has threads or other means for connecting the same to a conventional domestic water faucet carrying water under pressure, although the invention is not limited to use of water as one of the fluids to be mixed.

Referring now to FIGURE 1, it will be seen that, in accordance with the present invention, a fluid mixing device may comprise a casing 10 threaded at one end 11 thereof whereby the said casing may be connected with a source of fluid, such as water, under pressure. One or more other fluids, such as air or other gases, may be conducted into the casing 10 through lateral ducts such as ducts 12 and 13, either under their own pressure or through entrainment caused by the velocity of fluid flowing through a chamber 14 within the casing 10. The casing also includes a conical body 15 (see FIGURES 1 and 2) having tapering grooves or holes 16 formed therein and the said conical body 15 is threaded to the interior of casing 10 at locations 17. As will be apparent from the subsequent description, the grooves or holes 16 permit fluid flow from the source of pressure coupled to threads 11 to pass through casing 10 past the further fluid inlets 12 and 13 whereby a preliminary mixing of fluids may take place in the segmental chambers 14. In the particular arrangement shown in FIGURE 1, the conical body 15 is disposed closely adjacent to the interior of casing 10 and the said casing 10 includes on its interior surfaces a stepped shoulder 18 whereby the said conical body 15 cooperates with the interior of the casing 10 and particularly with the shoulder 18 thereof to provide an annular orifice of decreasing and thereafter of increasing diameter within casing 10.

In the operation of the structure thus shown in FIGURE 1, fluid passes into casing 10 at the upstream end thereof and this fluid thereafter passes through the grooves or apertures 16 in the tapered conical diaphragm body 15 and then passes through the aforementioned annular orifice defined by the outer surface of body 15 and the inner surface of casing 10 adjacent shoulder 18 to the mixing chamber 14 whereby a mixing of fluids takes place. These mixed fluids are thereafter further broken up and mixed by one or more screens 19 disposed downstream of the diaphragm structure 15 whereby an intimate mixture of fluids or aerated water issues from casing 10 at fluid outlet 20.

In the particular arrangement of FIGURE 1, the diaphragm body 15 is also attached to a rod 21 extending through screens 19 to the outlet opening 20 of the fluid

mixing device and the said rod 21 has a slot at the lowermost portion thereof for insertion of a coin whereby the diaphragm body 15 may be screwed or unscrewed within the casing 10 thereby to vary the dimensions of the annular orifice defined by the outer surface of body 15 and the inner surface of casing 10 adjacent shoulder 18. This particular adjustable feature of the embodiment shown in FIGURE 1 thus permits varying degrees of fluid mixing or aeration to take place and also provides means for readily compensating for changes in inlet pressure. In addition, it will be noted that by completely unscrewing the body 15 from the interior of casing 10, the parts of the fluid mixing device or aerator can be readily separated from one another thereby to permit ready cleaning of the several parts and the parts can thereafter be readily reassembled without the possibility of incorrect assembly and without the possibility of parts being lost.

Another arrangement constructed in accordance with the present invention and using webbed conical bodies to effect the function of diaphragms utilized heretofore, is illustrated in FIGURE 3. In this particular device, a circular row of four conical valves 30 are biased in place with respect to a ring structure 31 located within casing 32 by a spring 33. Casing 32 further includes a ring 34 disposed adjacent push rods 35 which are attached to the several conical valves 30 whereby, when the casing 32 is rotated clockwise, the said ring 34 will push against rods 35 thereby to lift the webbed conical diaphragm structures or valves 30 upward against the restraint of spring 33. A central webbed conical body 36 is also provided and this body 36 is connected with arms 37 which run diametrically across casing 32. Thus, when the casing 32 is being rotated counterclockwise or is being unscrewed, the spring 33 will depress valve bodies 30 thereby to seal the several orifices 38 in ring 31; and at the same time, the central conical body 36 will move downward whereby fluid under pressure will be admitted from the upstream end 39 of the overall arrangement and pass the webs of the body 36 to the mixing chamber 40.

In the particular arrangement of FIGURE 3, the second fluid inlet or air inlet is disposed on a lower surface of the overall fluid mixing device whereby air or other fluids enter the structure at orifices 41, and the desired mixing of air or fluids occurs in chamber 40. A rod having a head 42 is attached, as shown, to the central diaphragm structure 36 to prevent complete unscrewing of the casing 32 during use of the device. In the particular position illustration in FIGURE 3, fluid may pass through the central aperture of ring 31 adjacent diaphragm structure 36 but does not pass through the other apertures associated with the several diaphragm structures 30. When the casing 32 is rotated clockwise until the top of body 36 comes into contact with the under surface 43 of ring 31, then fluid will pass through the peripheral perforations associated with bodies 30 but will not pass through the central perforation of the structure. In intermediate positions of the casing 32, liquid will flow through both the central and peripheral apertures. This particular operation is described in detail in my aforementioned prior copending application Serial No. 135,645.

It will be noted that in the embodiment of FIGURE 3, the webbed conical body comprising the improved diaphragms of the present invention again cooperate with other portions of the aerator structure to provide a plurality of apertures for breaking up fluid passing through the aerating device, and while the arrangement of FIGURE 1 effects such cooperation between the webbed conical body and the casing itself, the arrangement of FIGURE 3 effects the desired cooperation between one or more webbed conical bodies and a ring disposed within the casing.

FIGURE 4 illustrates another embodiment of the invention operating essentially in the manner described in

reference to FIGURE 3, and this particular embodiment is somewhat simpler than that already described in reference to FIGURE 3. In the arrangement of FIGURE 4, a casing 50 may, as before, include internal threads 51 whereby the upstream end of the said casing may be attached to a source of fluid under pressure (for example a domestic water faucet) and the said casing 50 supports a ring-like structure 52 on the interior of the casing 50. Ring 52 includes a bore 53 on the lower surface thereof adapted to receive a webbed conical body 54 (see FIGURE 4A) and the lowermost portion of the said conical body 54 includes an elongated projection 55 which serves to support screens 56. As was the case in the arrangement of FIGURE 3, the casing further includes a plurality of air inlets 57 adjacent the downstream end thereof whereby air may pass through apertures 57 into a mixing chamber 58, and the overall structure comprising conical body 54 and screens 56 is retained within the casing by a collar 59 which is screwed into the lowermost portion of the casing.

In the operation of the particular aerator shown in FIGURE 4, water under pressure which is admitted to the casing at the upstream end thereof passes via an annular orifice 60 in ring 52 and the water is thereafter broken up as it passes through a plurality of longitudinal orifices of decreasing cross-section formed by webs 54a on the webbed conical body 54. The relatively high velocity streamlets of water so resulting thereafter pass to an enlarged mixing chamber 58 where they are intimately mixed with air or other fluids admitted at apertures 57 and the resulting aerated fluid is thereafter still further broken up by screens 56 and passes from the casing at the downstream end thereof via collar 59. It will be appreciated that by unscrewing collar 59, the body 54, together with screens 56, can be removed as a single unit and cleaned, and this single unit can thereafter be replaced readily without the possibility of incorrect replacement or loss of parts.

Still another arrangement similar to the structure already described in reference to FIGURE 1 is shown in FIGURE 5. In this particular arrangement, casing 60 again includes a plurality of internal threads 61 at the upstream end thereof for attachment to a source of fluid such as water under pressure and the said casing 60 also includes a diaphragm structure comprising a substantially conical body 62 similar to the conical body already described in reference to FIGURES 1 and 2. In particular, conical body 62 again includes a plurality of apertures or grooves 63 for permitting the flow of fluid past conical body 62, and past the shoulder 64 on casing 60, whereby air or other fluids admitted to the interior of the casing via inlets 65 is intimately mixed with the high pressure fluid in mixing chamber 66. The mixed fluids are thereafter further broken up by screens 67 and issue from the lowermost portion of the casing at 68. The particular structure shown in FIGURE 5 is quite simple and is easily manufactured, and this structure moreover includes the other advantages already described in that the diaphragm structure comprises a single removable unit 62 thereby permitting ready disassembly and cleaning of the overall device.

While I have described preferred embodiments of the present invention, many variations will be suggested to those skilled in the art, and therefore the foregoing description should be considered as merely illustrative and not limitative of my invention.

I claim to have invented:

1. In an aerator, jet forming means adapted at its upper end to be connected to a faucet and including two concentric members the inner one of which is easily removable from within the outer one; and the inner member having indentations in its upper outer periphery to there-

by provide a water passageway between the members; said members being spaced apart immediately below said passageway to thereby provide an annular chamber in communication with said passageway; the outer member extending downwardly and inwardly, intercepting the path of flow of the water passing through said passageway, to a position adjacent the inner member to provide at the lower end of said chamber an annular orifice of smaller cross-section than that of said chamber; means defining a mixing chamber below said annular orifice and in the path of flow of water therefrom and also defining an air inlet passing directly from the atmospheric air outside the aerator into said mixing chamber; and means for discharging the water from said mixing chamber in the form of a coherent jet laden with numerous small bubbles including mixing means in said mixing chamber for finely breaking up the water from said annular orifice and mixing it with air.

2. In an aerator as defined in claim 1, said mixing means including a part of said inner member which extends below said annular orifice.

3. In an aerator as defined in claim 2, said mixing means also including a screen across the outlet of the mixing chamber.

25 4. In an aerator as defined in claim 1, said last-named means also including a screen across the outlet of the mixing chamber.

5. In an aerator, jet forming means adapted at its upstream end to be connected to a faucet and including two concentric members the inner one of which is easily removable from within the outer one; said members defining between them an annular chamber which terminates at its downstream end in an annular orifice; at least one of said members defining a passageway through which water from the faucet may enter said annular chamber; one of said members as it passes to a lower level than the passageway extending under said passageway and receiving thereby the direct impact of water passing through the passageway and then extending further to a position adjacent the other member to thereby form said annular orifice; means defining a mixing chamber, at least a part of which mixing chamber is below said annular orifice for receiving water therefrom; said chamber having a side wall which defines an air inlet therethrough for supplying air directly from the atmosphere to said mixing chamber; and means for discharging the water from said mixing chamber in the form of a coherent jet laden with small bubbles including mixing means in the mixing chamber for receiving water from said annular orifice and mixing it with air.

40 6. In an aerator as defined in claim 5, said mixing means including a part of said inner member which extends below said annular orifice.
